INJECTOR

Charles H. True, Chicago, Ill., assignor to The
Superheater Company, New York, N. Y.

Application January 29, 1929. Serial No. 335,969

10 Claims. (Cl. 103—277)

My invention relates broadly to injectors and more specifically to exhaust steam injectors of the general type disclosed in United States Patent #1,342,128 granted June 1, 1920 to J. Metcalfe, et al.

In injectors of this general type, the combining tube of the injector is ordinarily provided with an overflow port controlled by a plug or flap pivotally mounted with respect to the combining tube, said flap being usually held in closed position by gravity and being opened by pressure within the combining tube to permit the discharge, through the injector overflow, of the initial steam and water admitted to the injector for the establishment of the jet which subsequently acts to deliver water under pressure from the injector.

In order to insure the highest efficiency in the operation of the injector, it is necessary for the combining tube flap to seat accurately, and the principal object of the present invention is the provision of a novel form of flap which may be more readily fitted to an accurate seat and maintained accurately seated than in the forms heretofore known. Another object of the invention is the provision of such a flap construction suitably adapted to mass production methods of manufacture at reduced cost. Further and more detailed objects of the invention, together with the benefits to be derived from its use, will become apparent from the ensuing detailed description of a preferred embodiment thereof illustrated in the accompanying drawings forming a part hereof, in which Fig. 1 is a longitudinal, vertical section taken through an injector of the class described; Fig. 2 is a similar section, on an enlarged scale, of the combining tube assembly shown in Fig. 1; Fig. 3 is a plan view of Fig. 2; Fig. 4 is a section taken on the line 4—4 of Fig. 1; and Fig. 5 is a section taken on the line 5—5 of Fig. 1.

Referring now to Fig. 1, the injector comprises a main casing A formed of two castings 1 and 2, the former containing the combining tube 3 and the delivery nozzle 4 and the latter containing the main low pressure steam nozzle 5, supplementary high pressure steam nozzle 6, water cone 7 and secondary low pressure steam nozzle 8. Exhaust steam is admitted through valve 9, supplementary high pressure steam through passage 10, auxiliary live steam through passage 11, and water through the chamber 12, while the overflow from the combining tube is carried from the injector through chamber 13 to the overflow outlet 14. Water under pres-

sure is delivered from the injector by way of the delivery conduit 15 controlled by the check valve 16. The structure thus far described is not novel, and as its operation is well known to those skilled in the art it is not deemed necessary to describe it in further detail herein.

Referring now to Figs. 2 and 3, the combining tube assembly comprises the main tube 3 of the usual form, which delivers across a small gap 17 in communication with chamber 13 to the entrance of the delivery nozzle 4. The upper side of tube 3 is formed with a lateral opening in which is seated the flap 18 carried by the longitudinally extending arm 19, the latter being pivoted at a point fixed relative to the nozzle by a transverse pin 20. Preferably the pin 20 is mounted in a suitably bored boss 21 carried by tube 3. In order to minimize wear, the pin 20 is made of hardened metal and is journaled in a hard metal bushing 22 in boss 21. Wear between the pin and the arm is prevented by the use of a cotter pin 23 passing through the pin and lying partially in a slot or groove cut in one face of arm 19, thus preventing rotation of the pin with respect to the arm.

At its free end, the arm 19 is bifurcated to form fingers 19a and 19b, each of which is bored to receive the transverse pin 24, and each of which has a plane lower surface 25 which seats against a cooperating surface milled on the upper side of flap 18 to prevent pivotal motion of the flap about pin 24, which passes through the fingers 19a, 19b and the suitably bored boss 26 on flap 18.

Intermediate the pins 20 and 24 a rectangular vertical hole is formed through arm 19 which provides lateral bearing faces 27 adapted to engage a suitable upstanding boss 28 on the tube 3, as will be seen from Fig. 4. As will readily be apparent from Fig. 2, sufficient longitudinal clearance between the boss 28 and the ends of the rectangular hole in the arm 19 is provided to permit of the oscillation of arm 19 about the pivot pin 20 without binding upon boss 28. The purpose of this boss is to provide a lateral bearing support serving to accurately center the flap 18 with respect to tube 3 and to prevent lateral displacement in case of wear in pin 20 or the surface in which it is journaled.

The tube 3 is preferably, although not necessarily, provided with transverse radial bores 29 which serve to connect the delivery end of the bore in the tube with the overflow chamber 13. The purpose of these will appear later.

The flap 18 seats against tube 3 on both sides of the central bore along the plane bearing surfaces 30, which are preferably located in the horizontal axial plane of the tube, these surfaces being joined at their ends by the transverse bearing surfaces 31 which are portions of the surface of a cone the axis of which lies transversely of the longitudinal axis of the tube 3.

With the flap 18 formed in this manner, it will be obvious that the bearing surfaces 31 on the flap may be readily formed in a lathe or other tool which revolves the flap about an axis vertical as viewed in Fig. 2 and that the bearing surfaces 30 may also be readily formed by a suitable facing tool while the flap is still chucked in such a machine. It will further be evident that the bearing surfaces of the lateral opening in tube 3 designed to receive flap 18 may be formed in a similar manner, that is, 10 either by a cutting tool acting on the tube 3 which is revolved about a properly centered axis at right angles to the longitudinal axis of the tube or by means of a suitably contoured boring or reaming tool revolving about such axis with the tube held in a fixed position. It will further be apparent that the bearing surfaces between tube 3 and flap 18 may be ground to a perfect fit by the simple expedient of oscillating the flap 18 in the opening in tube 3 before the former is 15 attached to arm 19, in much the same manner as the grinding in of an ordinary poppet valve. With the flap formed in accordance with the present invention, the free area through the lateral opening when the flap is lifted is somewhat 20 smaller than is the case with the prior known forms of flaps in which such transverse bearing surface as is required is ordinarily cut along an inclined plane transverse to the longitudinal axis of the tube, and for this reason I prefer to provide additional overflow area from the bore of tube 3 by means of the radial bores 29. These 25 bores are not essential to the successful operation of the injector, and it has been found that they do not affect the operation of the injector 30 adversely, even though they remain open at all 35 times.

While pivotal mounting of the flap with respect to the arm does not render the device inoperative, it has been found in practice that a 40 pivoted flap does not ordinarily return squarely to its seat, with the result that excessive wear occurs on the portions of the bearing surfaces where the flap first contacts with the tube. Such 45 wear obviously causes trouble due to excessive leakage around the flap.

In this connection it is to be noted that the flap does not extend to the delivery end of tube 3, so that the tube is solid at this point. This 50 construction has an important practical advantage, as the inlet end of the delivery nozzle 4 is subject to excessive erosion due to the extreme 55 velocity of the jet at this point. Ordinarily a renewable tip 32 is employed at this point, and it has been found that premature wear of this 60 tip has frequently been caused, in the older form of combining tube employing a flap extending to the delivery end of the tube, by a thin sheet of 65 water escaping through the joint between flap and tube and impinging on the end of the tip. 70 Obviously in the present form of construction, this cannot occur.

With the flap fixedly mounted on the arm 19, it is obvious that a regrinding of the flap which 75 would remove an appreciable amount of metal would, by lowering the flap, prevent its proper

seating unless the position of the flap with respect to the arm were changed. Such change, however, can readily be accomplished by filing the surfaces 25 to a new angle, and if much metal has to be removed, inserting shims between these surfaces and the flap.

While I have described my invention in conjunction with an exhaust steam injector of the horizontal type in which the combining tube flap is normally held in position by gravity, it will be obvious that the invention is applicable to other types of injectors, which may be positioned vertically as well as horizontally and which may employ other means for normally urging the combining tube flap to its seat. The embodiment herein shown is therefore to be considered as illustrative only and the invention is to be considered as limited only by the scope of the appended claims.

I claim:

1. In an injector, a combining tube having a lateral opening therein, the perimeter of which comprises conical surfaces, and a closure for said opening having complementary conical surfaces adapted to seat against the walls of said 100 port.

2. In an injector, a combining tube, an overflow chamber, a port in said tube affording communication between the bore of the combining tube and the overflow chamber, and means for closing said port, said means comprising a flap having conical bearing surfaces, and said port having complementary cooperating seating surfaces.

3. In an injector, a combining tube having a longitudinal conical bore therethrough and a lateral opening through said tube to said bore, the perimeter of said opening being defined by plane bearing surfaces lying in a common plane passing through the longitudinal axis of the tube 115 and connected by bearing surfaces forming portions of the surface of a cone the axis of which is normal to the plane of said first named bearing surfaces.

4. As a new article of manufacture, a flap 120 adapted to close the overflow opening in an injector combining tube, said flap being in the general form of a truncated cone and having conical bearing surfaces the corresponding portions of which are symmetrical with respect to 125 a central axis through said cone.

5. As a new article of manufacture, a flap 130 adapted to close the overflow opening in an injector combining tube, said flap being in the form of a section of a truncated cone and having oppositely disposed conical bearing surfaces the corresponding portions of which are symmetrical with respect to a central axis through 135 said flap, and plane bearing surfaces connecting the ends of said conical surfaces, said plane surfaces lying in a plane normal to said axis.

6. In an injector, a combining tube, an overflow chamber, a port in said tube affording communication between the bore of the combining tube and the overflow chamber, means for closing said port, said means comprising a pivot fixed with respect to said tube, an arm movable about said pivot, the free end of said arm being provided with a finger having a 145 plane bearing surface thereon, a flap adapted to seat in said port, said flap having a plane surface adapted to abut said first named surface to prevent relative motion between the flap and the arm, and a pin for removably securing 150

the flap to the arm with said surfaces in abutting relation.

7. In an injector, a combining tube having a longitudinal conical bore therethrough and a lateral opening through said tube to said bore, the perimeter of said opening being defined by two frusto-conical bearing surfaces whose axis is normal to the axis of the conical bore, and two plane surfaces at right angles to the axis 10 of the frusto-conical surfaces and extending between the two frusto-conical surfaces.

8. In an injector, a combining tube, an overflow chamber, a port in said tube affording communication between the bore of the combining 15 tube and the overflow chamber, the perimeter of said port comprising two frusto-conical surfaces, a closure for said port having complementary frusto-conical surfaces, and an arm carrying the closure and pivotally mounted on 20 the tube.

9. In an injector, a combining tube, an overflow chamber, a port in said tube affording communication between the bore of the combining tube and the overflow chamber, the perimeter of said port comprising two frusto-conical surfaces and two plane surfaces extending between them, a closure for the port having a complementary shape, and an arm carrying the closure and pivotally mounted on the tube. 80

10. In an injector, a combining tube having a longitudinal conical bore therethrough, and a lateral opening through said tube to said bore, the perimeter of said opening being defined by plane bearing surfaces lying in a common plane intersecting the bore longitudinally and connected by bearing surfaces forming portions of the surface of a cone whose axis is normal to the plane of said first named bearing surfaces. 85
